UNITED STATES PATENT OFFICE.

WILLIAM DIONNE, OF CHICAGO, ILLINOIS.

AERIAL APPARATUS.

Application filed March 7, 1927. Serial No. 173,364.

This invention relates to an aerial apparatus designed for use with a radio receiving set. It is of a type which may be contained within a housing easily portable and installable at any desired point interiorly of a building.

The present apparatus incorporates certain improvements in the direction of simplicity and compactness. It may conveniently be enclosed within a protective housing having a location adjacent to, or remote from, a receiving set. In addition, its antenna is comprised of a copper wire strung back and forth between two head plates, and a series of interconnected brass rods which assist in providing a rigid mounting for the head plates, all of the rods and wire stringings being serially connected. By this arrangement of the parts I provide a construction which is rugged and unusually effective in eliminating static.

My invention may take various forms of which one is suggested in the accompanying drawing in the manner following:

Figure 1 is a perspective view of the aerial apparatus with the protective cover therefor partly broken away;

Fig. 2 is a transverse section through the various wire stringings and rods forming the antenna;

Fig. 3 is a fragmentary detail in section showing the mounting for one wire and rod; and

Fig. 4 which is a similar view shows the connection at one end of the antenna.

The present apparatus may comprise a base A having upturned marginal edges 5 forming a shallow enclosure for the reception of the lower edges of a protective cover

B having a box-like structure. With the cover set in place upon the base, a completely protected compartment is provided. As by means of screws or hooks, not shown, the cover may be removably secured to the base. All of the parts just described may be made of any suitable material finished as desired.

Secured to the base in spaced relation to its several marginal edges, is a horizontal plate 6 to the opposite ends of which are connected upstanding head plates 7 and 8 made preferably from some insulated mate-

rial. Each head plate is formed with a plurality of aligned holes 9 and 10, the latter being the larger. The hole shown near the lower left corner of the proximate head plate 7 in Fig. 1 is of the larger size to accommodate an eye bolt 11 (see Fig. 4) which is desirably fastened in place by nuts 12 which bear upon opposite sides of the head plate. The bolt is disposed with its eye for convenient connection with one end of a copper wire 14 which is extended to the other head plate 8. This wire passes through an opening 9 therein in alignment with the eye bolt, and then around upon the outer side of the head plate to an adjacent opening through which it is strung back to the head plate 7. In like manner this wire for its entire length is strung back and forth between the two head plates which provide a mounting therefor.

In the form shown the wire stringings are located relatively close to the edges of the head plates. The end of the wire opposite to that which is connected with the eye bolt may be joined to a terminal 15 having an eye through which is received one end of a conductor rod 16, preferably of brass. These rods, of which several are shown, are all alike, as are also their mountings in the two head plates. The ends of each rod 16, as shown in Fig. 3, are threaded to receive a pair of nuts 12 arranged in each instance on opposite sides of the proximate head plate and adapted to bear with pressure thereupon when suitably adjusted. In this manner the rods are secured against movement, as are also the head plates which form mountings therefor.

As each rod is an independent unit, I provide between them serial connections adjacent outer sides of the two head plates. For this purpose, I may employ link bars 17 having at their opposite ends eyes which fit around the ends of the rods to be connected. After the nuts 12 are tightened in place, these link bars, as well as the terminal 15, are made secure so as to connect up in series the wire 14 as well as the several bars 16.

The construction thus far described is one which provides an antenna consisting of a continuous wire strung back and forth between the two head plates in connection with

a plurality of bars interconnected in series fashion. One end of the antenna is constituted by the eye bolt which, by means of the associated nuts 12, is adjustable to take up slack in the wire. A flat copper bar 18 formed preferably with eyes at each end, connects this bolt with a binding post 19, the bar extending first downwardly from the bolt and then horizontally to the post which 10 may be arranged adjacent one edge of the base A. A similar bar 20 having connection with a second binding post 21 extends also to the opposite antenna end formed by one of the rods 16.

15 An aerial apparatus so constructed constitutes a unit which is convenient for handling and installation, it being understood, of course, that suitable conductors are to be extended from one of the binding posts to 20 the antenna connection of the receiving set, and that another connection, if desired, is to be extended from the other post to the ground. In the exemplification shown, the parts forming the frame on which the antenna is carried are of light construction without sacrifice of sturdiness. This is due in part to the character of the two antenna components used, viz., the wire which tends to draw the two head plates together 25 and the rods which serve to hold them apart. In addition, the arrangement by which the wires are grouped around the rods is one which conduces to facility in assembly. This results from the fact that the frame 30 can be completely set up and made rigid by the use of the rods alone after which the wire can be strung back and forth without requiring further support for the head plates. It is not necessary, according to the 35 construction shown, to resort to solder connections at any point inasmuch as the several link bars may be preformed to fit accurately in their intended plates.

In the operation of the present apparatus 40 I have found that very satisfactory results are obtainable. By combining in an antenna a wire component formed of copper strands in the usual way with a number of connected brass bars having a cross sectional size 45 which is relatively large, I provide what is the equivalent of an aerial having a length considerably greater than the aggregate of the parts which are extended between the two head plates. Also because of the fact 50 that the conductivity of brass rods is slower than that of the copper strands, the flow of current is somewhat retarded, thus reducing to a large extent the interference which normally results from static.

60 I claim:

1. An aerial apparatus in which is combined a pair of spaced plates forming insulated mountings, conductor rods extended between the two plates, the ends of each rod 65 being threaded and inserted through open-

ings in the plates, a pair of nuts adjustably carried upon each rod end on opposite sides of the proximate plate, conductor means for serially connecting all the rods, and a wire conductor in series connection with the rods 70 strung back and forth between the plates and forming with the rods an antenna, substantially as described.

2. In an aerial apparatus, the combination of two apertured insulated plates in 75 spaced relation, conductor rods extended between the plates with their ends inserted through the apertures therein, means adjustably secured to the rods for engaging with opposite sides of each plate, conductor 80 means interconnecting the rods serially, and a conductor wire in series connection with the rods forming therewith an antenna, the wire being strung back and forth between the plates which serve as a support there- 85 for, substantially as described.

3. An aerial apparatus in which is combined a pair of apertured insulated plates in spaced relation, a plurality of conductor rods extended between the plates with the 90 rod ends inserted through the apertures therein, means for securing each rod against longitudinal movement within the plates, conductor means interconnecting all the rods in series, and a conductor wire strung back 95 and forth between the plates and passing through certain of the apertures therein having a series connection with the rods whereby to form therewith an antenna, substan- 100 tially as described.

4. In an aerial apparatus, the combination with a frame of a plurality of serially connected brass rods arranged in parallelism in a compact group, and a wire composed of copper strands serially connected with the 105 rods and strung back and forth in the frame in parallelism with the rods and disposed to the outside of the group thereof, the wire and rods together constituting an antenna, substantially as described. 110

5. In an aerial apparatus, the combination with a pair of apertured plates forming an insulated mounting of a plurality of grouped parallel conductor rods having their ends supported in the plates, means fixedly securing each rod to the said plates, conductor means serially connecting all of the rods, and a conductor wire in series connection with the rods strung back and forth between the two plates in parallelism with the rods and to the outside of the group thereof, the wire and rods together forming an antenna, substantially as described. 115

6. In an aerial apparatus, the combination with a frame of a conductor wire strung back and forth in the frame, a plurality of conductor rods parallel with the wire stringings also carried by the frame, conductor means serially connecting the rods and one end of the wire, and other conduc- 120 125 130

tor means adjustably connecting the opposite wire end to the frame, substantially as described.

7. An aerial apparatus having an antenna which comprises a wire formed of copper strands in series connection with a plurality of brass rods having a relatively greater

cross sectional area, the wire being arranged in parallel stringings and the rods also being parallel therewith, and a frame whereby to support the rods and wire stringings, substantially as described. 10

WILLIAM DIONNE.
